(57) CLAIM

The ornamental design for a basin, as shown and described.

DESCRIPTION

FIG. 1 is a perspective view of a basin showing our new design;

FIG. 2 is a top plan view thereof;

FIG. 3 is a front elevational view thereof;

FIG. 4 is a left side elevational view thereof; and,

FIG. 5 is a right side elevational view thereof.

The back and bottom sides of the basin are unornamented.
